UNITED STATES PATENT OFFICE

WILLIAM J. IRWIN, OF WILKINSBURG, PENNSYLVANIA

REGENERATIVE CHAMBER

Application filed July 6, 1932. Serial No. 631,119.

This invention relates to regenerative furnaces and particularly to the passageways or conduits which introduce the gaseous flows to the regenerator units. These are subject to the disadvantage that they do not distribute the gases so that an even uniform flow through the regenerator unit results. This causes hot and cold spots and prevents efficient furnace operation.

10 One of the objects of the present invention is to eliminate the above undesirable features of current regenerative furnace systems. Another object is to provide a construction which will effect this improvement without incidentally materially increasing the construction costs. Other objects may be inferred from the following disclosure of various specific forms of the invention as applied to an open hearth's regenerator.

15 20 Having reference to the accompanying drawings:

Figure 1 is a horizontal cross-section taken from the broken line I—I in Figure 3.

Figures 2 and 3 are vertical cross-sections 25 from the broken lines II—II and III—III in Figure 1, and

Figures 4 and 5 are cross-sections from the lines IV—IV and V—V in Figure 1.

The above show a brick or tile checker-work 1 having an upper chamber 2 and a lower chamber 3. The upper chamber is connected to the furnace's combustion chamber by an uptake 4 and slag pockets 5, and its lower chamber is connected by a flue 6 to either a stack, gas or air main, depending upon the furnace's heating cycle and whether this particular unit is preheating air or gas. Although the usual brick checkerwork is illustrated, it is to be understood that the invention is applicable to any form of heat regenerator unit.

The uneven flow through the checkerwork 1 mentioned in the forepart of the specification results from the velocity of the gases through the chambers 2 or 3, which carries it to their ends and there forces it upwardly or downwardly. Thus the most cooled part receives the least heat and the most heated part receives the least of the gases to be cooled.

In the present instance the top chamber's neck 7 is constructed with a downwardly inclined roof 8 which is shaped to create a directed gas impingement against this end of the checkerwork 1, which is the point ordinarily receiving the least flow. Also, the flue 6 is constructed to angle upwardly, its gases striking the bottom of the checkerwork 1 near the flue's mouth. This last also creates a directed gas impingement against the bottom of the checkerwork 1 adjacent the flue's mouth, which is another point heretofore ordinarily receiving the least flow.

The above construction causes a substantially even gaseous flow through the checker-work 1 because the gaseous stream strikes the checkerwork with their full velocities at the points which are normally neglected. The roofs of the chambers 2 and 3 are preferably constructed to gradually approach the surfaces of the checkerwork 1, and the gases which are deflected after impinging the checkerwork 1 at their points of entrance pass to the ends of these chambers and are gradually forced through the checkerwork.

The essential feature of this invention is the direction of the gases' flow against that part of the checkerwork which is normally neglected. Therefore, the flue 6, and the roof 8 of the neck 7 should merge smoothly with the top and bottom of the chambers 2 and 3 so that a true directed gas flow results.

As far as described, the invention applies particularly to a regenerator unit to whose chambers the gaseous flows are introduced in alignment with their longitudinal center lines. In practice, however, the flow introduction is frequently at an angle to these center lines. This also causes the aforementioned difficulties and may be remedied by the invention.

Such undesirable effects may be diminished by deflectors 9 which tend to guide the gaseous stream towards the most neglected points. These points normally appear in the corners 95 of the regenerator unit adjacent that side of the passageways forming obtuse angles therewith. Preferably, these deflectors are in the form of a halved pyramid whose base and side portions fit the passageways' corners 100

which are most remote from the regenerator unit. Their apices do not completely reach to the other extreme of the side walls of these passageways. This leaves straight portions 9^a on the original passageways and prevents a pocketing action of the gaseous flow. Also, the various proportions and shapes of all the disclosed matter may be changed to accommodate operating conditions encountered.

Although a specific form of this invention has been shown and described in accordance with the patent statutes, it is not intended to limit the scope thereof exactly thereto, except as defined by the following claims.

I claim:

1. The combination of a heat regenerating unit, chambers extending the lengths of the open sides of said unit, and passageways communicating with one end of each of said chambers at opposite ends of said unit, one or more of said passageways being constructed so their surfaces remote from said unit angle theretowards and terminate thereover.

2. The combination of a heat regenerating unit, chambers extending the lengths of the open sides of said unit, passageways communicating with one end of each of said chambers at opposite ends of said unit and at an angle thereto, and one or more deflectors arranged adjacent said unit and on the sides of one or more of said passageways forming acute angles therewith.

3. The combination of a heat regenerating unit, chambers extending the lengths of the open sides of said unit, passageways communicating with one end of each of said chambers at opposite ends of said unit and one or more being at an angle thereto, and pyramidal deflectors constructed and arranged in the corner portions of one or more of said passageways remote from said unit and on their side or sides forming acute angles therewith.

4. The combination of a heat regenerating unit, chambers extending the lengths of the open sides of said unit, passageways communicating with one end of each of said chambers at opposite ends of said unit and at an angle thereto, pyramidal deflectors constructed and arranged in the corner portions of said passageways remote from said unit and on their sides forming acute angles therewith, the apex portions of said deflectors merging with the sides of said passageways on which they are constructed before reaching the opposite corner portions of those sides.

5. The combination of a heat regenerating unit, chambers extending the length of said unit to the top and bottom sides thereof, passageways communicating with one end of each of said chambers at opposite ends of said unit and terminating over said unit, the pas-

sageway communicating with said bottom chamber extending upwardly on an angle so as to direct the gases passing therethrough upwardly into the unit, the passageway communicating with said upper chamber having its upper wall inclined downwardly to direct the gases passing through said passageway downwardly into said unit, and a deflector arranged adjacent said unit in at least one of said passageways for further deflecting the gases into said unit.

6. The combination of a heat regenerating unit, an intake passage that deviates side-wise to the regenerator unit, a deflector located on the side of the passage that forms an acute angle with the adjoining side of the regenerator unit in plan, said deflector being of variable width as seen in successive cross-sections at right angles to the axis of the passage, and the maximum width of each cross-section being adjacent that side of said passage most remote from said unit.

In testimony whereof, I have hereunto set my hand.

WILLIAM J. IRWIN.

CERTIFICATE OF CORRECTION.

Patent No. 1,904,237.

April 18, 1933.

WILLIAM J. IRWIN.

It is hereby certified that error appears in the printed specification of the above numbered patent requiring correction as follows: Page 2, line 53, claim 4, for "remove" read "remote"; and that the said Letters Patent should be read with this correction therein that the same may conform to the record of the case in the Patent Office.

Signed and sealed this 13th day of June, A. D. 1933.

M. J. Moore.
